ABSTRACT

A slub yarn having a hand spun silk yarn-like appearance and feel to the hand is continuously produced from a multifilament yarn by feeding the multifilament yarn into a reduced pressure region formed in a hollow column at a predetermined feed rate while vigorously sucking air from the atmosphere through the region, agitating the multifilament yarn by the sucked air current to convert portions of the yarn into slubs consisting of portions of the yarn and/or the individual filaments entangled, intertwined, looped, bent and/or folded by action of the sucked air vortex or turbulent current, and delivering the resultant slub yarn from the reduced pressure region at a delivery rate lower than the feed rate.

PROCESS AND APPARATUS FOR CONTINUOUSLY PRODUCING SLUB YARN

The present invention relates to a process and apparatus for producing a multifilament fancy yarn, more particularly, it relates to a process and apparatus for continuously producing a multifilament slub yarn suitable for forming a silk shun tung-like fabric.

The term "silk shun tung" used here refers to a hand-made fabric of a hand spun silk yarn which is uneven in thickness. This hand spun silk yarn has slubs and knots formed thereon.

According to the general accepted idea, the principal purpose of weaving and knitting is to provide a fabric having a desired appearance and feel to the hand. In this regard, the silk fabric called shun tung received universal commendation when it appeared because of its grain, elegant and naive appearance and feel to the hand.

There have been attempts to produce an artificial filament fancy yarn having a hand spun silk yarn-like appearance and feel. In the most conventionally used of these attempts the yarn is produced, using a fancy twister, by intermittently twining a multifilament yarn about a multifilament core yarn to form slubs and then, bonding the slub-forming yarn and the core yarn with a multifilament bonding yarn. In the conventional method stated above, the resultant fancy yarn feels hard to the hand because the component yarns are firmly twisted. Accordingly, the fabric made of the conventional fancy yarn feels too hard even though the fabric has the shun tung-like appearance.

It is known from other attempts that the hand spun silk yarn-like fancy yarn is produced by feeding at least one multifilament yarn intermittently and at least one multifilament yarn continuously into a zone blown by a fluid jet. By the action of the fluid jet, the individual filaments in the yarns are entangled and, intertwined with each other. That is, the continuously fed yarn is converted to slubs formed on the intermittently fed yarn.

However, the known process stated above has the following disadvantages.

1. High cost in production, because two or more component multifilaments are necessary for producing only one fancy yarn.

2. Very complicated production apparatus, because one or more component yarns must be intermittently fed to the twister.

3. Undesirable formation of a wood grain-like pattern or tortoise shell pattern on the fabric, because the slubs are formed on the yarn at fixed intervals.

4. Low efficiency in energy utilization of the fluid jet.

5. Low production velocity.

An object of the present invention is to provide a process and apparatus for continuously producing slub yarns having a hand spun silk yarn-like appearance, a soft feel to the hand and high processability, with high efficiency and at a high production velocity.

The other object of the present invention is to provide a process and apparatus for continuously producing slub yarns having slubs firmly bundled on the yarn, using a simple slub-forming means.

The above-stated objects can be accomplished by the process and apparatus of the present invention. According to the process of the present invention, a slub yarn is continuously produced by the steps of providing a reduced pressure region by sucking air from the at-

mosphere through the region, feeding a multifilament yarn into the reduced pressure region at a predetermined feed rate while continuing to suck the air through the reduced pressure region, agitating the fed

5 yarn within the reduced pressure region by the action of the sucked air current to convert portions of the fed yarn into slubs consisting of entangled, intertwined and/or folded portions of said yarn and/or individual filaments in said yarn, and delivering the resultant slub

10 yarn from the reduced pressure region at a delivery rate lower than the feed rate.

The apparatus of the present invention comprises a slub-forming device comprising a hollow column having a yarn supply end plate with a yarn supply hole

15 formed thereon and a yarn delivery end plate with a yarn supply hole formed thereon, means for feeding a multifilament yarn into said slub-forming device at a predetermined feed rate, and means for delivering the slub yarn from said slub-forming device at a delivery

20 rate lower than the feed rate, the slub-forming device being connected at its periphery to a vacuum device through an air suction pipe.

When the multifilament yarn is fed into the reduced pressure region formed in the slub-forming device at a

25 feed rate higher than the delivery rate, the multifilament yarn is agitated by the action of air stream vigorously sucked from the atmosphere through the yarn supply and delivery holes into the reduced pressure region. As a result of the agitation, portions of the multi-

30 filament yarn and/or portions of individual filaments in the yarn are entangled, intertwined, folded and/or bent to form the slubs on the yarn. The portions of the yarn are converted into the slubs in response to the difference between the feed rate and the delivery rate. That

35 is, not all of the multifilament yarn is converted into slubs. While the multifilament yarn fed into the reduced pressure region is agitated by the action of the sucked air stream and vigorously moves throughout the region, some portions of the yarn or the individual filaments are rubbed with other portions of the yarn, other

40 filaments or the inside wall surface of the slub-forming device so as to produce static electricity thereon. This static electricity generated on some portions of the yarn or individual filaments can promote the entangle-

45 ment, intertwining bending and/or folding of the yarns and/or the individual filaments. The generation of the static electricity is effected irregular and at unfixed intervals of time on portions of the yarn or the individual filaments. This causes irregular distribution and un-

50 fixed lengths and thicknesses of the slubs.

The reduced pressure region is formed in a slub-forming device by vigorously sucking air with a vacuum device from the atmosphere through the yarn supply hole, yarn delivery hole and the slub-forming device.

55 The sucked air generates vigorous vortexes or turbulent currents in the slub-forming device. The vigorous air vortexes or turbulent currents can agitate the multifilament yarn to open it into separate individual filaments and entangle, intertwine, bend and/or fold the

60 individual filaments. The type and amount of the air vortexes or turbulent currents are in response to the type of slub-forming device and capacity of the vacuum device. The vacuum device usable for the apparatus of the present invention may be a vacuum pump, suction

65 fan or ejector.

In the process of the present invention, the multifilament yarn is preferably fed upward into the reduced pressure region and travels upward through the region

and then, the slub yarn is delivered upward from the region. However, the yarn may travel downward or laterally.

The features and advantages of the present invention will be apparent to persons acquainted with this type of fancy yarn upon reading the following descriptions and referring to the accompanying drawings, in which:

FIG. 1 shows an explanatory view of an embodiment of the apparatus of the present invention;

FIG. 2 shows an explanatory cross-sectional view of an embodiment of a slub-forming device with an air suction pipe, usable for the apparatus of the present invention;

FIG. 3 is an explanatory cross-sectional view of an embodiment of a slub-forming device with an air suction pipe and an air permeable partition disposed in the slub-forming device, usable for the apparatus of the present invention;

FIG. 4 is an explanatory cross-sectional view of an embodiment of a slub-forming device with an air suction pipe and an air permeable partition located in the air suction pipe, usable for the apparatus of the present invention;

FIG. 5 is an explanatory cross-sectional view of an embodiment of a slub-forming device with an air suction pipe, a yarn storage inner tube disposed in a yarn supply end portion of the slub-forming device and an air suction member located in a yarn delivery end portion of the slub-forming device, usable for the apparatus of the present invention;

FIG. 6 shows a cross-section of the air suction member shown in FIG. 5, along line VI—VI in FIG. 5;

FIG. 7 shows a cross-section of the slub-forming device shown in FIG. 5, along line VII—VII in FIG. 5;

FIG. 8 is an explanatory cross-sectional view of an embodiment of a slub-forming device with an air suction pipe, an air suction member, a yarn storage inner hollow column and an air vortex inner hollow column disposed between the air suction member and the yarn storage inner hollow column, usable for the apparatus of the present invention;

FIG. 9 shows a cross-section of the slub-forming device shown in FIG. 8, along line IX—IX in FIG. 8, and;

FIGS. 10 and 11 respectively show an explanatory view of an embodiment of the slub yarn produced in accordance with the present invention.

The process of the present invention may be carried out by the apparatus as shown in FIG. 1. In the drawing, a multifilament yarn 1 is taken from a yarn supply package 2 by means of a pair of feed rollers 3a and 3b and fed into a slub-forming device 4 at a predetermined feed rate. The slub-forming device 4 is connected to a vacuum device 5 through an air suction pipe 6 to define therein a reduced pressure region. When the vacuum device 5 is actuated, the reduced pressure region is formed in the slub-forming device 4, and air is vigorously sucked from the atmosphere into the slub-forming device 4. The sucked air produces a vigorous vortex or turbulent current in the slub-forming device. By the action of the sucked air current, the multifilament yarn is converted into a slub yarn 7 having slubs 7a while the multifilament yarn is in the slub-forming device 4. The slub yarn 7 is removed from the slub-forming device 4 by means of a delivery roller 8 at a delivery rate lower than the feed rate, and wound up into a yarn take up package 9.

As stated above, while the multifilament yarn 1 is in the slub-forming device 4, the yarn 1 is vigorously agi-

tated by the action of the air vortex or turbulent current. This agitation results in looping, bending, folding and opening of the multifilament yarn and entanglement, intertwining, looping, bending and folding of the separated individual filaments. These movements of the yarn and individual filaments cause the irregular formation of slubs on the yarn. That is, some portions of the multifilament yarn are converted to slubs having irregular length and thickness and such slubs are distributed at irregular intervals along the length of the yarn, and other portions of the multifilament yarn are re-bundled while travelling from the slub-forming device 4 to the take up package 9.

The multifilament yarns usable for the process of the present invention may be selected conventional natural and artificial multifilament yarns. The natural multifilament yarn may be a silk yarn. The artificial multifilament yarn may be a regenerated cellulose multifilament yarn, for example, viscose rayon or cuprammonium rayon yarn, regenerated protein multifilament yarn, semi-synthetic multifilament yarn, for example, cellulose diacetate or cellulose triacetate filament yarn, and synthetic multifilament yarn made of a fiber-forming synthetic polymer, for example, polyester such as polyethylene terephthalate, polybutylene terephthalate, polyoxyethylene benzoate or polyethylene terephthalate-type copolymers containing isophthalic acid, phthalic acid, adipic acid, sebatic acid, diethylene glycol or polyethylene glycol and copolymers of these; polyamide such as nylon 6, nylon 66, nylon 610, nylon 12, polyamide including cyclohexane groups, polyamide including isophthalic acid, phthalic acid or terephthalic acid or these copolymer; polyamidoether; polyolefin such as polyethylene, polypropylene or ethylene-propylene copolymer; and acrylic polymer such as polyacrylonitrile or acrylonitrile copolymer.

It is desirable that the multifilament yarn usable for the present invention be easily opened by the action of the air vortex or turbulent current produced in the slub-forming device. For this purpose firmly twisted multifilament yarns are firmly bonded multifilament yarns with a sizing agent are not suitable because they are difficult to open. However, the firmly twisted and sized multifilament yarns may be used for the process of the present invention if at least one other multifilament yarn which can be easily opened, is used, as a slub-forming yarn, together with them.

Referring to FIG. 1, the feed means 3a and 3b for the multifilament yarn 1 feed the yarn at a constant rate without slippage of the yarn on the feed means. The feed means may be of any type, for example, a pair of nip rollers as shown in FIG. 1, apron rollers or Nelson's rollers.

The winding up means for the slub yarn may be a conventional winder capable of taking up the slub yarn at a desired constant rate. For the process of the present invention, a conventional RT winder having no transverse guide and traveller is preferable rather than a conventional spindle drive winder or QT winder which have the traverse guide and traveller. This is because the slubs formed on the slub yarn of the present invention tend to restrict passage of the yarn through the traverse guide and traveller. This is because the slubs have a larger thickness than that of the original multifilament yarn and, therefore, are frequently caught in the traverse guide and traveller.

The slub-forming device for forming therein the reduced pressure region, will be explained in detail by re-

5
ferring to FIGS. 2 through 9 of the accompanying drawings.

FIG. 2 shows a longitudinal cross-sectional view of a simple embodiment of the slab-forming device. The slab-forming device 11 has a hollow column 12, a yarn supply end plate 13 and a yarn delivery end plate 15. The yarn supply end plate 13 has a yarn supply hole 14 formed in the center of the plate 13. The yarn delivery end plate 15 has a yarn delivery hole 16 formed in the center of the plate 15. One end of an air suction pipe 17 is connected to a middle portion of the wall of the hollow column 12. The other end of the air suction pipe 17 is connected to a vacuum device (not shown in FIG. 2) such as a vacuum pump.

When the vacuum device is actuated, the pressure of the hollow column 12 is reduced, and air is sucked at a high flow rate from the atmosphere through the yarn supply and delivery holes 14 and 16 into the hollow column 12. The air thus sucked generates under a reduced pressure an air vortex or turbulent current in the hollow column 12.

The multifilament yarn, together with the sucked air, is fed into the hollow column 12 through the yarn supply hole 14 and vigorously agitated by the action of the air current. During the agitating, portions of the multifilament yarn 1 are converted into slubs 7a distributed randomly along the yarn 7.

Sometimes, portions of the yarn 1 are sucked from the hollow column 12 into the air suction pipe 17 and converted into slubs having a relatively long length.

The hollow column 12 may have a circular cross-sectional profile or an irregular cross-sectional profile, for example, square, hexagonal, octagonal and oval cross-sectional profiles.

In FIG. 3, the slab-forming device 21 is similar to the slab-forming device 11 shown in FIG. 2 except that the hollow column 12 is divided into two compartments by an air permeable partition 22. The partition 22 is perforated and has a plurality of small holes 23. The partition 22 is arranged parallel to the yarn travel path from the yarn supply hole 14 to the yarn delivery hole 16, between the yarn travel path and the end of the air suction pipe 17 connected to the wall of the hollow column 12. That is, one of the compartments is connected to the vacuum device (not shown in FIG. 3) through the air suction pipe 17 and the other compartment is connected to the atmosphere through the yarn supply and delivery holes 14 and 16. Only air, and not, the multifilament yarn can pass through the small holes 23 of the partition 22. The perforated partition 22 may be a 20 to 100 mesh net.

When the vacuum device (not shown) is actuated, air is sucked from atmosphere through the yarn supply and delivery holes 14 and 16 into the hollow column 12 at a very high flow rate. A portion of the sucked air collides with the partition 22 and the other portion passes through the small holes 23 of the partition 22. The passing of the sucked air through the small holes 23 of the partition 22 causes suction of the multifilament yarn onto the surface of the partition 22 and the multifilament yarn temporarily stays on the partition surface 22. The collision of a portion of the sucked air with the partition 22 results in very vigorous agitation of the multifilament yarn which has been sucked onto the partition. While in the hollow column 12, the multifilament yarn 1 is prevented by the partition 22 from suction into the air suction pipe 17. This prevention is effective for promoting the formation of relatively uni-

5
form slubs in length, thickness and distribution. This is because the condition of the multifilament yarn staying in the slab-forming device 21 is relatively uniform throughout the operation time. In the embodiment of the apparatus as shown in FIG. 3, the hollow column preferably has an irregular cross-sectional profile, for example, square, hexagonal and octagonal cross-sectional profiles.

inside diameter of the yarn storage inner hollow column 42. The yarn travel path passes through the center opening 46 of the air suction member 45. The air suction member 45 is provided with one or more air suction holes 47 through which the center opening 46 is connected to the atmosphere. The air suction hole 47 is formed in such a manner that the longitudinal axis of the air suction hole 47 does not intersect the longitudinal axis of the center opening 46. The air suction holes 47 thus formed are effective for generating a vortex of the sucked air in the slab-forming device 41.

Referring to FIG. 7, the holes 43 are formed through the wall of the yarn storage inner hollow column 42 in such a manner that the longitudinal axes of the holes 43 do not intersect the longitudinal axis of the yarn storage inner hollow column 42. The holes 43 are effective for promoting the formation of vortex of the sucked air in the yarn storage inner hollow column 42. The holes 43 may be formed in such a manner that the longitudinal axes of the holes 43 intersect the longitudinal axis of the yarn storage inner hollow column.

When the vacuum device (not shown in FIG. 5) is actuated, air is sucked from the atmosphere into the slab-forming device 41 through the yarn supply and delivery holes 14 and 16 and the air suction holes 47 of the air suction member 45. The air sucked through the air suction holes 47 and the yarn delivery hole 16 is formed into a vortex in the center opening 46, and further sucked into the air suction pipe 17. The air sucked into the yarn storage inner hollow column 42 through the yarn supply hole 14 is further sucked into the suction pipe 17 through the holes 43 and also the opening 45 and clearance 48. Accordingly, in the yarn delivery end portion of the yarn storage inner hollow column 42, air flows upward from the middle portion thereof and in the yarn supply end portion of the inner hollow column 42, air flows downward from the middle portion. That is, the sucked air in the yarn storage inner hollow column 42 is formed into two currents in opposite directions to each other. Therefore, the middle portion of the yarn storage inner hollow column 42 is reduced into a lower pressure than the other portions. In the middle portion, the turbulent air current is most vigorous. When the multifilament yarn 1 is fed into the yarn storage inner hollow column 42 through the yarn supply hole 14, the yarn 1 is vigorously agitated in the middle portion. While passing through the center opening 46 of the air suction member 45, the agitated yarn 1 is re-bundled by the air vortex.

Referring to FIG. 8, the slab-forming device 51 is provided with an air vortex inner hollow column 52 extending from the air suction member 45 toward the yarn storage inner hollow column 42. The hollow space of the air vortex inner hollow column 52 is connected with the center opening 46 of the air suction member 45. The end of the air vortex inner hollow column 52 facing the open end 44 of the yarn storage inner hollow column 42, is closed with an end member 53 having a funnel-shaped inside surface 54 and a hole 55 through which the yarn travels. Further, the air vortex inner hollow column 52 has a plurality of holes 56 formed in the side walls thereof. Referring to FIG. 9, the holes 56 are formed through the side walls of the air vortex inner hollow column 52 in such a manner that the longitudinal axes of the holes 56 do not intersect the longitudinal axis of the air vortex inner hollow column 52.

The multifilament yarn is vigorously agitated in the middle portion of the yarn storage inner hollow column

42, and travels into the air vortex inner hollow column 52 through the hole 55. The air vortex inner hollow column 52 strengthens the air vortex produced by the air suction member 45. Accordingly, while traveling through the air vortex inner hollow column 52 and the center opening 46 of the air suction member 45, the agitated yarn is re-bundled. That is, the slab-forming device 51 of FIG. 8 is effective for producing a compact slab yarn. The air vortex inner hollow column may be of a circular cross-sectional profile or an irregular cross-sectional profile, for example, square, hexagonal, octagonal and oval cross-sectional profiles.

The hollow column 12 and the yarn storage inner hollow column 42 wherein the slubs are formed, may have an inside wall surface containing sharply edged fine particles. Some of the individual filaments agitated in the slab-forming device come into contact with the abrasive surface containing the sharply edged particles and are broken. The broken filaments form fluffs on the yarn. Therefore, the resultant slab yarn has a spun slab yarn-like appearance but is made of the multifilament yarn.

The abrasive surface carries thereon numerous fine abrasive grains having a high hardness and sharp edges to scratch or break the filaments. The abrasive surface may be an abrasive sheet such as sand paper or sand cloth, on which numerous abrasive grains are fixed with a binder.

The abrasive grains preferably consist of a metallic material such as carbon steel quenched by high frequency induction process, or an inorganic material such as diamond, boron carbide, silicon carbide, crystallized alumina, molten zircon, garnet, jade and rock crystal, silica, molten quartz, orthoclase and apatite, or mixtures of two or more of these materials. The abrasive grains preferably have a size of 16 to 250 μ and are preferably distributed in a density of 50 grains/cm² or more.

The slab-forming devices usable for the present invention are not limited to those as shown in FIGS. 2 through 9. Rather, these FIGS. merely illustrate particular preferred embodiments of the present invention. It will be recognized that variations and modifications of the disclosed apparatus including the rearrangement of parts, lie within the scope of the present invention.

FIGS. 10 and 11 show explanatory views of slab yarns produced by the present invention, respectively. In FIG. 10, the slab is formed from complicitely entangled, intertwined, folded and/or looped individual filaments separated from each other. In FIG. 11, the slab is formed by a portion of the yarn being folded and intertwined with itself.

In the process of the present invention, the pattern of the slab to be produced is in response to condition of the sucked air current under a reduced pressure and the overfeed ratio. The term "overfeed ratio" used here refers to a ratio in percent of the difference between the feed rate and the delivery rate of the multifilament yarn to the delivery rate.

The condition of the sucked air current depends on the type of the slab-forming device, and has an influence upon the configuration and length of the slubs. The overfeed ratio influences the frequency of the slab formation and length of the slab.

In the process of the present invention, the overfeed ratio may be varied within a range of from 5 to 300%. Accordingly, by adjusting the overfeed ratio and selecting the type of the slab-forming device, almost all pat-

terns of slub yarns can be obtained.

Depending upon the overfeed ratio, type of the slub-forming device and degree of vacuum, sometimes, the resultant slub yarn has slubs formed by loosely entangling and intertwining the yarn and/or individual filaments. Such slubs are very bulky. Therefore, in the travelling of the slub yarn, the loosely formed slubs are frequently restricted by the yarn guide in a rewinding, weaving or knitting machine. The interruption results in breakage of the slub yarn. Accordingly, the slub yarn having such loosely formed slubs cannot be used for rewinding, weaving and knitting. In this case, the defect as stated above can be eliminated by the following methods:

1. Firmly re-bundling the slub yarn removed from the slub-forming device by blowing a jet of air onto the slub yarn.

2. Firmly bonding the slub yarn by applying a bonding agent, such as sizing agent and resin.

3. Tightening the slub yarn by passing through a high temperature zone to shrink the looped filaments and loosely entangled yarn and filaments.

Otherwise, in order to produce firmly bundled slub yarn, it is effective to lightly twist the multifilament yarn in a small number of twists before feeding it into the slub-forming device, to lightly interlace the individual filaments by blowing a jet of air onto the yarn before the slub-forming. The twisting and interlacing stated above are effective for controlling the opening of the multifilament yarn.

The multifilament yarn usable for the present invention may be composed of a single multifilament yarn or two or more component multifilament yarns. The component multifilament yarns may be the same as or different from each other. The different component multifilament yarns may be different in type of polymer, denier of the yarn or individual filament, number of individual filaments and type of process applied to the yarn. That is, the multifilament yarn may be a crimped yarn, textured yarn or regular yarn, or a doubled yarn of a crimped or textured yarn and a regular yarn. Also, the multifilament yarn may consist of two or more thermoplastic polymer component yarns different in melting point from each other. The slub yarn produced by the present invention may be further subjected to a crimping or texturing process such as stuffing crimping and false-twisting.

In the case where the slub yarn consists of two or more thermoplastic polymer yarns different in melting point from each other, the slub yarn may be heat treated at a temperature lower than the lighter melting point but not lower than the lower melting point of the yarns. By the heat treatment, the higher melting point yarn is firmly bonded by the melted lower melting point yarn.

As stated hereinbefore, energy efficiency of the process of the present invention is higher than the conventional slub-forming methods wherein a fluid jet is blown onto the yarn, because the slub-forming is effected in a reduced pressure region wherein the yarn and individual filaments can easily move. Further, the apparatus of the present invention involves no twisting means and mechanism for forming slubs at random which are necessary for the conventional slub forming apparatuses. Therefore, the apparatus of the present invention is very simple in structure and of low cost, and can be driven at a very high velocity.

The following examples are presented merely for the purpose of illustrating the present invention.

EXAMPLES 1 THROUGH 30

- 5 As shown in Table 1, in Example 1, a polyethylene terephthalate multifilament yarn of 100 denier consisting of 48 filaments (100 d/48 f) was twisted at a twist number of 10 turns per meter (10 T/M). The twisted yarn was processed in the apparatus as shown in FIG. 1 10 having the slub-forming device as shown in FIG. 2 under conditions as shown in Table 1, columns 4, 5, 6 and 7. In Table 1, column 6, the term "overfeed ratio" refers to a ratio in % of the difference between the feed rate and delivery rate of the yarn for the slub-forming device to the delivery rate. The processed yarn had the properties as shown in Table 2. In Table 2, the term "frequency in forming of slub" refers to the number of slubs formed in a 100 m length of the processed yarn. 15 The same procedures as in Example 1 were repeated 20 in Examples 2 through 4, respectively, using the slub-forming device shown in FIGS. 3 through 5, under conditions detailed in Table 1. The properties of the slub-formed yarns in Examples 2 through 4 are shown in Table 2. 25 The same procedures as in Example 1 through 4 were repeated in Examples 5 through 30, under the conditions and using the yarn and the slub-forming device as shown for each example in Table 1. The slub-formed yarns in Examples 5 through 30 had the properties 30 shown in Table 2.

Referring to Tables 1 and 2, the processed yarns in Examples 1, 5, 9, 10, 11, 15, 19 and 23, which had been slub-formed by the slub-forming device of FIG. 2, had slub lengths varying in a wide range.

35 The slub-formed yarns in Examples 2, 6, 12, 16, 20, 24 and 25 using the slub-forming device of FIG. 3 had relatively short and thick slubs. The yarns slub-formed in Examples 3, 7, 13, 17, 21, 26 and 27 using the slub-forming device of FIG. 4 had relatively long and thin 40 slubs. In Examples 4, 8, 14, 18, 22, 28, 29 and 30 using the slub-forming device as shown in FIG. 5, the processed yarns had relatively thin and short slubs which were slightly different, in thickness and appearance, from the non slub-forming portion of the yarn.

45 From Tables 1 and 2, it is clear that the process and apparatus of the present invention are applicable for all types in material of multifilament yarns because neither heat nor chemicals are used for the slub-forming. The patterns of the slubs formed by the process of the present invention vary, in length, thickness and configuration, in response to the type of slub-forming device used. Further, it should be noted that the process of the present invention is applicable to any type in configuration of regular multifilament yarns, textured yarns, composite yarns of regular yarn with textured yarn and composite yarns of two or more same or different types of textured yarns. That is, the patterns of the formed slubs can be varied simply by varying the type of slub-forming device and the slub-forming condition. The 50 slub yarns produced in Examples 1 through 30 were similar in weaving property to the conventional twisted slub yarns, and somewhat poorer than the regular twisted yarns because the slubs sometimes cause breakage of the yarn. The frequency of the yarn breakages depends on the pattern of the slubs. The fabrics produced from the slub yarns of Examples 1 through 30 were all uniform in appearance, having no unevenness in a tortoise-shell pattern or wood grain pattern. These 55 60 65

fabrics each had a very soft feel to the hand because the yarn was not twisted during the slab-forming process. Further, since the regular portions of the slab yarn are somewhat dishevelled in parallel arrangement of the individual filaments by the action of the sucked air current, the fabrics had silk fabric-like luster due to desirable diffused reflection of light at the regular portions of the slab yarns in the fabrics.

Some of the slab yarns in these examples had loops formed by the dishevelled individual filaments in the 10 slubs and the regular portions of the yarns.

EXAMPLES 31 THROUGH 33

In Example 31, the same procedures as in Example 1 were repeated using the same apparatus as shown in FIGS. 1 and 2 except that an interlace nozzle was arranged between the slab-forming device and the delivery roller 8 and compressed air of a 3 kg/cm² pressure was ejected onto the slab-formed yarn through the interlace nozzle.

In Example 32, the same procedures as in Example 31 were repeated using, instead of the interlace nozzle, a rotatable sizing roller located between slab-forming device and the delivery roller 8. A lower portion of the sizing roller was immersed in a bath containing an aqueous solution of 3% by weight of polyvinyl alcohol. The slab-formed yarn delivered from the slab-forming device was brought into contact with an upper portion of the sizing roller, carrying on its periphery surface a polyvinyl alcohol solution, and sized.

In Example 33, the same procedures as in Example 31 were repeated using, instead of the interlace nozzle, a hot plate of a 1 m length placed between the slab-forming device and the delivery roller. The hot plate was heated at a temperature of 230°C, and the slab-formed yarn delivered from the slab-forming device came into contact with the heating surface of the hot plate. The resultant slab yarns in Examples 31 through 33 were remarkably improved in the bundling of the individual filaments in the slab portions and the regular portions of the slab yarns. That is, in these slab yarns disheveling of the individual filaments was prevented. This is similar to the conventional twisted slab yarns.

The slab yarn of Example 31 had small loops of the filaments. However, the processability in weaving and knitting of the slab yarn was similar to that of the regular multifilament yarns. The slab yarns of Examples 32 and 33 had much less filament loops and were similar in processability to the regular yarns.

Further, it should be noted that even in the cases where the interlace nozzle, sizing roller or hot plate was located between the slab-forming device was the delivery roller to bundle the individual filaments in the slab 5 yarn, the resultant slab yarn had no change in slab pattern, that is, frequency in slab forming and length and thickness of the slubs.

Additionally, the same procedures as in Examples 31 through 33 were repeated using the same starting yarn 10 under the same process conditions as those in Examples 2, 3, 4, 19, 20, 21 or 22. All of the procedures were carried out without difficulty, and the resultant slab 15 yarns were improved in bundling of the individual filaments.

EXAMPLES 34 THROUGH 41

The same slab yarns as produced in Examples 1 through 4 and 19 through 22 were crimped using a gear crimping machine having a heater device located up-

20 stream of the crimping gear. The crimped slab yarns were used to produce fabrics. The resultant fabrics had a high bulkiness and very soft feel to the hand. The heater device located upstream of the crimping gear was effective for improving the bundling of the individual filaments in the slab yarns. Therefore, the crimped 25 slab yarns were woven into uniform fabrics without difficulty.

The same procedures as in Examples 34 through 41 were repeated using, instead of the gear crimping machine, a frictional false-twisting device. The resultant 30 fabrics were highly bulky and very soft. The false-twisting device was provided with a heater located upstream from a friction drive means. The heater was effective for bundling the individual filaments in the slab yarns.

EXAMPLES 42 THROUGH 49

An interlace nozzle was located upstream of the feed roller in the apparatus shown in FIG. 1. In Example 42, the same procedures as in Example 1 were repeated

40 using the above-mentioned apparatus. Before the slab-forming step, the starting yarn was lightly bundled by the action of a compressed air current spouted through the interlace nozzle under a pressure of 0.5 kg/cm². The processed yarn had the properties as shown in 45 Table 3.

In Examples 43 through 49, the same procedures as in Examples 2 through 4 and 19 through 22, respectively, were repeated using the above-mentioned apparatus. The properties of the resultant slab yarns are 50 shown in Table 3.

Table 3

Ex. No.	Starting yarn and process conditions	Slub-yarn				
		Mean length of slubs (cm)	Largest length of slubs (cm)	Frequency in slab- forming	Weaving property	Loop forming
42	as Example 1	41	115	26	slightly poor	ordinal
43	as Example 2	26	41	53	normal	ordinal
44	as Example 3	40	153	14	slightly poor	less ordinal
45	as Example 4	6	19	113	normal	less
46	as Example 19	15	38	19	slightly poor	ordinal
47	as Example 20	10	37	24	normal	less
48	as Example 21	20	135	13	slightly poor	ordinal
49	as Example 22	5	15	125	good	less ordinal

15

The spouting of the compressed air resulted in slightly bundling the individual filaments in the starting yarn. The bundling caused difficulty in the opening of the individual filaments in the slab-forming step. Less opening of the individual filaments resulted in less entanglements, interwindings and loopings of the individual filaments. Accordingly, Table 3 shows that the resultant slab yarns had less frequency of slab-forming and larger slab length than those in Examples 1 through 4 and 19 through 22. Further, the loopformation in Examples 42 through 49 was less than in the corresponding foregoing examples. Therefore, the slab yarns obtained in the present examples had regular (non slab-formed) portions similar in appearance to the starting yarn.

EXAMPLE 50

A hot plate of a 1 m length was inserted between the slab-forming device and the delivery roller in apparatus shown in FIG. 1. The hot plate was maintained at a temperature of 170°C to heat the slab yarn delivered from the slab-forming device.

A polyethylene terephthalate multifilaments yarn of a 300 denier consisting of 36 filaments and having a twist number of 10 T/M was doubled with a polypropylene yarn of 30 denier consisting of 7 filaments and having a twist number of 10 T/M and the doubled yarn was fed into the above-stated apparatus having slab-forming device as shown in FIG. 5 to convert it into a slab yarn. The fed doubled yarn was processed under the following conditions.

Feed rate	345 m/min
Wind-up (delivery) rate	300 m/min
Degree of vacuum	50 mmHg
Heater temperature	170°C

When the doubled yarn came into contact with the heater plate, the polypropylene yarn was melted in parts and bonded the individual polyethylene terephthalate filaments and the remaining polypropylene filaments in the slab yarn. The loops formed on the slab yarn were shrunk by the contact with the heater plate. Accordingly, the resultant slab yarn has a high processability in winding, weaving and knitting.

The same procedures as in the present example were repeated using, instead of the slab-forming device of FIG. 5, the slab-forming device of FIGS. 2, 3 and 4. The resultant slab yarns were similar in processability to the yarn in the present example.

What we claim is:

1. A process for continuously producing slab yarns comprising the steps of:

providing a reduced pressure region in a closed hollow column and connected to the atmosphere through a yarn supply hole at an end of said column and a yarn delivery hole located at an opposite end of said column, by sucking air from the atmosphere through said region;

feeding a multifilament yarn into said reduced pressure region through said yarn supply hole at predetermined feed rate while sucking air through said region;

agitating said fed multifilament yarn in said reduced pressure region by action of the sucked air current in order to convert portions of said multifilament yarn into slubs; and

16

delivering said resultant slab yarn from said reduced pressure region through said yarn delivery hole at a delivery rate lower than said feed rate.

2. A process as claimed in claim 1, wherein said fed multifilament yarn is sucked onto an air-permeable surface provided within said reduced pressure region.

3. A process as claimed in claim 2, wherein said fed multifilament yarn temporarily stays on said air-permeable surface.

4. A process as claimed in claim 1, wherein said sucked air is formed into two currents in opposite directions to each other within said reduced pressure region.

5. A process as claimed in claim 1, wherein said slab yarn delivered from said reduced pressure region is rebundled by the action of an air jet blown onto the slab yarn.

6. A process as claimed in claim 1, wherein said slab yarn delivered from said reduced pressure region is bonded by applying a bonding agent to the slab yarn.

7. A process as claimed in claim 1, wherein said slab yarn delivered from said reduced pressure region is tightened by heating it at a temperature at which the looped or loosely entangled individual filaments shrink.

8. A process as claimed in claim 1, wherein said multifilament yarn is lightly bundled before feeding it into said reduced pressure region.

9. A process as claimed in claim 1, wherein said multifilament yarn is a crimped or textured yarn.

10. A process as claimed in claim 1, wherein said multifilament yarn consists of two or more component multifilament yarns.

11. A process as claimed in claim 10, wherein said component yarns are the same.

12. A process as claimed in claim 10, wherein said component yarns are different from each other.

13. A process as claimed in claim 12, wherein said component yarns are one or more crimped multifilament yarns and one or more regular multifilament yarns.

14. A process as claimed in claim 12, wherein said component yarns are thermoplastic polymer multifilament yarns different in melting point from each other.

15. A process as claimed in claim 14, wherein said slab yarn consisting of said thermoplastic polymer multifilament yarns different in melting point from each other, is heat treated at a temperature lower than the higher melting point but not lower than the lower melting point of said thermoplastic polymer multifilament yarns.

16. A process as claimed in claim 1, wherein a ratio of difference between said feed rate and said delivery rate to said delivery rate is in a range from 5 to 300%.

17. A process as claimed in claim 1, wherein said yarn is, after slab-forming, further re-bundled within said reduced pressure region by action of a vortex of the sucked air.

18. A process as claimed in claim 1, wherein said yarn travels upward.

19. An apparatus for continuously producing a slab yarn from a multifilament yarn, comprising:

a slab-forming device comprising a closed hollow column having a yarn supply plate located at an end of said column and having a yarn supply hole formed thereon and a yarn delivery plate located at an opposite end of said column and having a yarn delivery hole formed thereon;

feed means for feeding a multifilament yarn at a predetermined feed rate into said slab-forming device through said yarn supply hole; delivery means for delivering a slab-yarn at a predetermined delivery rate lower than said feed rate from said slab-forming device through said yarn delivery hole, and;

means for sucking air from the atmosphere through said slab-forming device, said means being connected to the periphery of said hollow column.

20. The apparatus of claim 19 wherein said means for sucking air is connected to the periphery of said hollow column by a pipe.

21. An apparatus as claimed in claim 20, wherein said pipe is provided with an air permeable partition located therein.

22. An apparatus as claimed in claim 19, wherein said hollow column has a circular cross-sectional profile.

23. An apparatus as claimed in claim 19, wherein said hollow column has an irregular cross-sectional profile.

24. An apparatus as claimed in claim 19, wherein said hollow column of said slab-forming device is divided into two compartments with an air permeable partition disposed in parallel to the yarn travel path from the yarn supply hole to the yarn delivery hole, between the yarn travel path and the entrance of said air suction means.

25. An apparatus as claimed in claim 24, wherein said hollow column has a square cross-sectional profile.

26. An apparatus as claimed in claim 19, wherein said hollow column of said slab-forming device has a yarn storage inner hollow column located therein and surrounding the yarn travel path between said yarn supply hole and the yarn delivery hole, said yarn storage inner hollow column having a yarn supply end connected to the yarn supply end plate of said hollow column, the other end opening in said hollow column and

a plurality of small holes formed on the yarn supply end portion thereof.

27. An apparatus as claimed in claim 26, wherein said small holes on said inner hollow column are formed in such a manner that the longitudinal axes of said holes do not intersect the longitudinal axis of said yarn storage inner hollow column.

28. An apparatus as claimed in claim 26, wherein said small holes on said inner hollow column are formed in such a manner that the longitudinal axes of said holes intersect the longitudinal axis of said yarn storage inner hollow column.

29. An apparatus as claimed in claim 26, wherein said hollow column further comprises an air suction member located between said yarn delivery end plate and said yarn storage inner hollow column and having a center opening and one or more air suction holes through which said center opening is connected to atmosphere, said air suction holes being formed in such a manner that the longitudinal axes of said air suction holes do not intersect with the longitudinal axis of said center opening.

30. An apparatus as claimed in claim 29, wherein said hollow column of said slab-forming device is further provided with an air vortex inner hollow column extending from said air suction member toward said yarn storage inner hollow column and surrounding said yarn travel path, said air vortex inner hollow column having a plurality of small holes formed on its periphery in such a manner that the longitudinal axes of the holes do not intersect with the longitudinal axis of the air vortex inner hollow column, and a hole formed on its one end facing said yarn storage inner hollow column.

31. An apparatus as claimed in claim 26, wherein said yarn storage inner hollow column has an inside wall surface containing sharply edged fine particles.

32. An apparatus as claimed in claim 19, wherein said hollow column has an inside wall surface made of sharply edged fine particles.
